UNITED STATES PATENT OFFICE.

MATTHEW L. TEAFF, OF DENNISON, OHIO.

STOVE FOR CARS, STEAMBOATS, &c.

SPECIFICATION forming part of Letters Patent No. 394,795, dated December 18, 1888.

Application filed March 31, 1888. Serial No. 269,069. (No model.)

To all whom it may concern:

Be it known that I, MATTHEW L. TEAFF, a citizen of the United States, residing at Dennison, in the county of Tuscarawas and State 5 of Ohio, have invented certain new and useful Improvements in Stoves for Cars, Steam-boats, &c.; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 This invention relates to safety or fire-proof stoves, or, more properly speaking, a safe or case for a stove for railroad-cars, steamboats, and for conveyances generally, of whatever nature, that are required to be heated and 20 which are likely to be overturned and upset the stove and spill the hot coals.

The object of the invention is the provision 25 of a safe or case to receive the stove, and which, in the event of accident, will automatically close every inlet and outlet thereto and absolutely cut off every avenue to the escape 30 of hot coals, thereby preventing fire being communicated to the car or other conveyance, which is oftentimes more fatal in its consequences than the accident to the said car or 35 conveyance itself. This case not only serves as an envelope for the stove, but forms a hot-air chamber from which heated air may be conveyed to different parts of the apartment 40 in which it is placed, or to other apartments. The case will be made entirely of metal, plate-steel, malleable and homogeneous, being best adapted for the purpose because of its flexible and tenacious nature. These plates will 45 be bolted together in any desired manner, and the case will be appropriately finished and ornamented to give it a pleasing and, imposing appearance.

The improvement consists of the novel features which hereinafter will be more fully described, and particularly pointed out in the claims, and shown in the annexed drawings, in which—

50 Figure 1 is a front view of a stove or case embodying my invention; Fig. 2, a side view, parts being broken away, of the stove or case; Fig. 3, a detail side view showing the hot-air-

pipe cut-off and the means for locking and operating it; Fig. 4, a horizontal section on the line X X of Fig. 2; Fig. 5, a vertical section on the line Y Y of Fig. 3; Fig. 6, a top plan view of the case, the cap being removed; Fig. 7, a bottom plan view of the case; Fig. 8, a sectional detail of the bottom of the case, showing the spring-catch for holding the door 60 closed against the bottom of the case; and Fig. 9, a detail section on the line z z of Fig. 6.

The case A, which may be of any suitable outline in cross-section, is composed of the 65 sides A', A², A³, and A⁴, the top A⁵, and the bottom A⁶, and is supported above the floor, preferably on the feet A⁷.

The stove B, of desired pattern, is placed 70 within the case, the stove and case being so proportioned that ample space is left between the stove and the case to permit the sides of the case from becoming heated to such an extent that it would scorch a fabric placed 75 against it. The stove-pipe b extends through an opening in the top of the case and through coincident openings in the guide-plate C, the cutting-plates C' C², and the cap C³, and is provided with the heating-drum b', which is cylindrical and has corrugated heat-radiating 80 ends b². The plates forming the sides of the case have their edges flanged and securely bolted or riveted together, and are re-enforced at the corners by the angle-irons a.

The top and bottom are bolted to the top 85 and bottom flanges of the plates.

The plate A' is constructed to slide to place from above, being left unbolted to permit the stove being placed in position. When the stove is in place, the side A' is adjusted and 90 bolted. This side is provided with the two doors a' and a², through which access is had to the fire-pot and ash-pit of the stove. These doors are securely locked at all times except when the stove is receiving attention.

95 The bottom A⁶ is perforated to admit air to the stove and to the interior of the case, and is provided with the door D, which is adapted to close the openings in the bottom. The springs E, secured at one end to the bottom 100 A⁶ and having their free ends bearing on the lateral arms d of the door D, exert a pressure to force the said door shut when it is released, being normally held open by the hook d',

which engages a staple or eyelet in the floor. The brackets *e*, secured to the bottom *A*⁶, limit the downward movement of the door. The double spring-catch *e'*, depending from the bottom *A*⁶, locks the door *D* when closed.

The hot-air pipe *F* connects with the chest *F'*, that is secured to a side of the case, and the cut-off *F*², that works through the case, has an opening to register with the openings in the side of the chest and case. This cut-off is forced up by any means to shut off communication between the hot-air pipe and the chest, preferably by the spring *f*, mounted on the pull-rod *f'* and held between the bottom *A*⁶ and the arm *f*². The arm *f*² is apertured to permit the passage of the pull-rod *f'*, and its outer end passes through the cut-off. The lower end of the pull-rod extends through the bottom *A*⁶ and is fastened to the floor by the hook *f*³. The upper end of the cut-off is beveled to form the arrow-shaped head *f*⁶ with notches *f*⁴ in its edges, in which the ends of the double spring-clutch *G* fit and hold the cut-off up when closed.

25 The guide-plate *C* has cross grooves or channels, in which the cutting-plates *C'* and *C*² are fitted and work, the edges of the channels being undercut to receive the edges of the cutting-plates. The ends of the cutting-
30 plates project beyond the sides of the case a suitable distance and have stops formed by thickening the ends of the plates, which prevent the plates from slipping out endwise. The openings in the plates *C'* and *C*² have
35 their edges beveled to a knife-edge, so that they will readily sever the pipe in the event of the stove toppling over or being struck a smart blow.

The spring *f* is protected by the housing *H*,
40 and is located within the case, so as to be out of the way.

When the stove is adjusted in the desired position, it is held by any suitable fastening devices or means to prevent it shifting. The pull-rod *f* is held down by the hook *f*³, driven in the floor, and the link *f*⁵. The door *D* is held open against the tension of the springs *E* by the link *d'* and the eyelet *d*², driven in the floor. In the event of an accident sufficient to dislodge the stove, the fastenings between the pull-rod and the floor and between the door *D* and the floor will be broken and the cut-off will close the hot-air opening, and the door *D* will close the openings in the said bottom, each being operated and locked by the means hereinbefore described. If the stove should overturn or strike the side of the vehicle or conveyance, the cutting-plates, having their ends projecting beyond the sides of
55 the stove, will be the first to strike, and, moving in, will sever the pipe. The cutting-plate is limited in its inward movement by the stop hereinbefore mentioned, and is prevented from moving out by coming in con-

tact with the object against which it first impacted, and which forms a support for the stove.

Having thus described my invention, what I claim, and desire to secure by Letters Patent, is—

1. The combination, with the herein-described safe or case for a stove, having a smoke-pipe, of a cutting-plate to sever the smoke-pipe and close the opening through which the said smoke-pipe projects, substantially as described.

2. The combination, with the case having a smoke-pipe, of the cutting-plate for severing the said smoke-pipe, having its end extended beyond the side of the case, substantially as described.

3. The combination, with the case having a smoke-pipe, of the cutting-plates for severing the said smoke-pipe, crossing each other and having their ends projecting beyond the sides of the case, substantially as and for the purpose set forth.

4. The combination, with the case having a smoke-pipe and the guide-plate having cross-channels, of the cutting-plates for severing the said smoke-pipe, fitted in the channels and having the stops at their ends, substantially as and for the purpose described.

5. In a car-heater, the combination, with the case having an opening in its side, the chest secured to the exterior of the case and having openings coinciding with the opening in the said case, and the cut-off adapted to reciprocate in the said chest and having an arrow-shaped head, *f*⁶, provided with notches in its edges, of the double spring-clutch *G*, for engaging with the said notches for locking the cut-off, and the spring for actuating the cut-off when the said cut-off is released, substantially as described.

6. The combination, with the case, the chest secured to the sides of the case, and the cut-off working through the chest, of the pull-rod located in the chest, the spring on the pull-rod, the arm projecting from the pull-rod and extending through an opening in the case and connecting with the said cut-off, and the housing arranged over the said pull-rod, the spring, and the said opening, substantially as shown and described.

7. The combination, with the case having a perforated bottom and the door provided with lateral arms, of the two springs secured at one end to the bottom and having their free ends bearing on the said arms, substantially as and for the purpose described.

In testimony whereof I affix my signature in presence of two witnesses.

MATTHEW L. TEAFF.
